UNITED STATES PATENT OFFICE

107,260

DESIGN FOR A SHOE OR SIMILAR ARTICLE

Morris Rosenston, Boston, Mass.

Application October 30, 1937, Serial No. 72,530

Term of patent 3½ years

To all whom it may concern:

Be it known that I, Morris Rosenston, a citizen of the United States, residing at Boston, in the county of Suffolk and State of Massachusetts, have invented a new, original, and ornamental Design for a Shoe or Similar Article, of which the following is a specification, reference being had to the accompanying drawing forming part thereof.

The drawing is a perspective view of a shoe or similar article showing my new design.

I claim:

The ornamental design for a shoe or similar article, substantially as shown.

MORRIS ROSENSTON.
